DEEP WELL PUMPING APPARATUS

Filed Feb. 21, 1931

UNITED STATES PATENT OFFICE

JOHN WALTER CHANCELLOR, OF BOWIE, TEXAS

DEEP WELL PUMPING APPARATUS

Application filed February 21, 1931. Serial No. 517,574.

My invention relates to pumping apparatus and especially to pumps suitable for deep well operation.

An object of my invention is to provide a pumping apparatus which by its structure will produce a continuous flow of liquid and which is controlled so as to operate with the greatest efficiency.

Another object is to provide a pump which is simple in structure and efficient due to a limited number of parts, yet capable of producing results only obtained by pumps heretofore having more or less complicated structure.

15 Referring to the accompanying drawing, which is made a part hereof and on which similar reference characters indicate similar parts,

Figure 1 is a perspective of the pumping system with parts shown in section,

20 Figure 2, a plan view of the air controlling mechanism,

Figure 3, a section view on line 3-3 of Figure 2,

25 Figure 4, a section view on line 4-4 of Figure 1, and

Figure 5, a modified form of the air controlling mechanism with parts shown in section.

30 In the drawing, reference character 10 represents the bore of a well in which a portion of the pumping apparatus is placed, this portion consisting of cylinders 11 and 12 mounted in superposed fashion but separate from each other. The cylinders are provided with integral partitions 13 and 14 respectively dividing the cylinders into two parts, the larger of which forms the inlet side and the smaller the discharge side thereof. The 35 partition 13 in cylinder 11 extends the full length and completely separates the inlet from the outlet side. In the lower cylinder 12, the partition 14 extends downwardly but does not reach the bottom thereby allowing 40 liquid to flow from one side to the other. The cylinders are provided with narrow inlet openings 15 and 16 respectively extending almost the entire length of the cylinders, each provided with inwardly extending valve 45 seats on which rest flaps 17 and 18 these being

hinged at 19 and 20 and operating within the cylinders. The length of the cylinders may vary and in order to insure quick filling any number of additional inlet valves may be used.

55 A pipe 21 connects the discharge pipes of the two cylinders and is provided with a one-way valve 22 which permits liquid to pass from the discharge side of cylinder 12 to the discharge side of cylinder 11 and outward to a common discharge pipe 23 to any desired point, this pipe 23 being connected to the upper end of the discharge side of cylinder 11.

60 A pipe 24 is connected to the bottom of cylinder 11 and is joined to pipe 21 at a point 25 intermediate the valve 22 and the lower end of the discharge side of cylinder 11 and is provided with a one-way valve 26, similar to valve 22, permitting liquid to pass from the 65 cylinder 11 to pipe 21, hence outward through the common discharge 23. Pipes 27 and 28 connected to the upper ends of the cylinders 11 and 12 respectively and convey the operating fluid to the cylinders from a control mechanism as will now be described.

65 The control mechanism consists of a valve structure 29. The upper portion 30 is provided with an outwardly extending flange 31 on its lower edge and an arm 32. The lower portion 33 is cup-like in structure and has a flange 34, corresponding to flange 31, on its upper edge by which the parts 30 and 33 are secured together by any suitable means. The center portion 35 of the valve is nested in the 70 lower portion 33 and provided with packing rings 36 to form a tight but rotatable connection with respect to the upper and lower portions. The center portion 35 is provided 75 with inlet passage ways 37 and 38 each diametrically opposite exhaust ports 39 and 40 respectively. The inlet passages extend through this portion and in line with the corresponding passages in the upper and lower 80 portions depending on the position of the center portion. The exhaust ports extend partially into the center portion and are turned at right angles to the outside edge. 85 Corresponding ports 41 and 42 are bored in 90 95 100

the lower section to conform with the exhaust ports 40 and 39 respectively.

A lever 43, extending through a slot 43' in the lower portion 33 is connected to the center portion and is operated by a rod having a slotted bar 44 on one end and connected at the other end to a piston 45 operable in a cylinder 46'. The piston 45 is operated by means of compressed air from the pipes 27 and 28 and conveyed to each side of the piston by pipes 46 and 47. The needle valves 48 and 49 control the flow of the air to the cylinder 46'.

A pin 50 secured to the lever 43 extends into the slot in the bar 44 serving as a connection between the rotating portion 35 and the piston 45. A pin 51 of greater length than pin 50 is fixed to the lever 43 and spaced from the slotted bar 44 at a distance to move without engaging the bar. A similar pin 52 is secured to the arm 32 and a spring 53 is connected between the last named pins serving to snap the mechanism back and forth as the spring moves in and out of parallel alignment with the lever 43.

The lower portion of the valve structure is connected to pipes 27 and 28 and the upper portion to pipes 54 and 55 which merge into a single supply pipe 56 connected to a tank 57 of compressed gas or air and supplied by the pipe 58 from a compressor not shown.

In the modified form Fig. 5 a valve operating on the same principle as that just described is shown but of slightly different structure. The valve consists of a sliding central portion 59 provided with passages 60 and 61 and exhaust ports 62 and 63. The upper section 64 and the lower section 65 are secured together by any suitable means. A bar 66 is secured or made integral with the sliding section 59 and is provided with a pin 67 at its free end. The slotted end 68 of the piston rod 70 engages the pin 67, said slotted end 68 being actuated by a piston 71 on the piston rod 70 operating in cylinder 72. The piston is operable by compressed air or gas from lines 73 and 74 connected to line 75 and 76 respectively which carry air to the main cylinders in the well from the control valve. Pipes 77 and 78 supply the main valve with compressed air from a suitable supply.

A curved bracket 79 is mounted on the upper section 64 of the valve and is provided with a link 80 pivoted to its free end at 81. The link 80 is provided with a slot 82 which engages a pin 83 on the bar 66. The free end of the link 80 is connected to a point 84 of the bracket 79 by a spring 85 in a manner to move with the bar 66 to the right or left as the case may be and cause a snap movement of the bar 66 as the spring 85 moves in and out of parallel alignment with respect to the link 80.

The operation of the above described apparatus is as follows:

Compressed air or gas flows from the supply tank or any suitable source through the main pipe line 56 and hence to the valve which is in the position as indicated by Fig. 2. The passage way 38 is in line with the pipes 53 and 27 permitting the operating fluid to flow into the pipe 27 forcing the valve 17 shut and the liquid which is in the cylinder 11 through the pipe 24, pipe 21 and then outward through the pipe 23. Valve 22 prevents the liquid from entering the cylinder 12. At the same time part of the compressed air enters the pipe 46 and the piston 45 is gradually moved to the right forcing the slotted bar 44 carrying the lever 43, and rotating the section 35 slowly in a counter-clockwise direction until the spring has passed a line parallel with the lever and then it will snap to its extreme position due to the action of the spring. As the compressed air enters the cylinder 11 the valve 18 in the cylinder 12 opens, the incoming water forcing the trapped air upward through the pipe 28 which is in line with the exhaust port 40. As soon as the piston 45 has reached the position opposite to that shown in Figure 2 the passageway 37 is then in line with the pipes 28 and 55, the exhaust port 39 lines up with the pipe 27. Air is forced through the pipe 28 to the cylinder 12 forcing the valve 18 shut and the liquid outwardly through the discharge side into the pipe 21 and thence to the discharge pipe 23. The valve 26 prevents the liquid from entering the cylinder 11. Meanwhile the incoming water against the valve 17 in the cylinder 11 forces the air out of this cylinder through the pipe 27 to the exhaust port 39, thus completing one pumping stroke of the pumping apparatus and which always insures constant flow of water from the cylinders. The rapidity of operating is controlled by the needle valves 48 and 49 to the valve operating piston. The form shown in Figure 5 operates substantially the same in principle excepting for a sliding horizontal rather than rotatable control valve.

It will be obvious to those skilled in the art that various changes may be made in my device without departing from the spirit of the invention and therefore I do not limit myself to what is shown in the drawing and described in the specification, but only as indicated by the appended claims.

Having thus fully described my said invention, what I claim as new and desire to secure by Letters Patent, is:

1. A pump suitable for deep wells comprising a plurality of cylinders having inlet and outlet valves, a discharge pipe connected to said cylinders, supply pipes for the pumping fluid connected to each of the said cylinders, a rotating disc valve for controlling the flow of the pumping fluid to the cylinders, and means for actuating said rotating valve,

said means comprising an air operated piston actuated by compressed air from said supply pipes, substantially as set forth.

2. A pumping apparatus comprising pumping cylinders provided with integral partitions dividing the cylinders into inlet and discharge chambers, means for connecting said inlet and discharge chambers, a main discharge connected to said discharge chambers, an air supply pipe to each cylinder, and means for regulating the supply through said supply pipes to the cylinders, said means comprising a valve having a movable center section, a lever connected to said section, a piston operating said lever, and resilient means for quickening the movement of said rotating section by the lever, substantially as set forth.

3. A compressed air pump comprising a pair of pumping cylinders, a source of compressed air, a valve for controlling admission of air to the cylinders, and an air motor for operating said valve actuated by air from said valve, substantially as set forth.

4. An air actuated fluid pump comprising a pair of pumping cylinders having inlet and outlet for fluid to be pumped and having inlets for compressed air for effecting the pumping, a source of compressed air, a valve controlling passage of air from said source alternately to the said cylinders, a motor for operating said valve, said motor being operated by air from the said valve, substantially as set forth.

5. An air lift pump comprising a pair of pumping cylinders having inlet and outlet for fluid to be pumped and having inlets for compressed air for effecting the pumping, a source of compressed air, a valve controlling passage of air from said source alternately to the said cylinders, a motor for operating said valve, said motor being operated by air from the said source, and manually operable valves for controlling the said motor to regulate the speed of operation of the said pump, substantially as set forth.

6. A compressed air pump comprising a pair of cylinders having inlet and outlet passages for fluid to be pumped, a tank containing compressed air, air conduits from said tank to said cylinders, a valve in said conduits for delivering air alternately to said cylinders, a motor for operating said valve, said motor being operated by compressed air exhausted from the said valve, substantially as set forth.

7. A compressed air pump comprising a pair of pumping cylinders, a source of compressed air, a valve controlling the flow of air from said source alternately to said cylinders, means for operating said valve, said means being operated by compressed air controlled by said valve, substantially as set forth.

8. A pump suitable for deep wells comprising a plurality of cylinders having inlet and outlet valves, a discharge pipe connected to said cylinders, a source of pumping fluid, supply pipes for the pumping fluid connected to each of the said cylinders, a valve for controlling the flow of the pumping fluid to the cylinders, and a piston for actuating said valve being driven by the pumping fluid exhausted from said valve, substantially as set forth.

70
75

ing a plurality of cylinders having inlet and outlet valves, a discharge pipe connected to said cylinders, a source of pumping fluid, supply pipes for the pumping fluid connected to each of the said cylinders, a valve for controlling the flow of the pumping fluid to the cylinders, and a piston for actuating said valve being driven by the pumping fluid exhausted from said valve, substantially as set forth.

75
80
85

9. A pump suitable for deep wells comprising a plurality of pumping cylinders, inlet valves mounted within said cylinders, a discharge pipe extending upwardly through said cylinders, supply pipes connected to said cylinders for supplying the pumping fluid, a valve connected in said supply lines provided with a movable center portion, a lever secured to said portion, and pressure means for actuating said lever to actuate said center portion thereby controlling flow through the supply lines, substantially as set forth.

85
90

In witness whereof, I have hereunto set my hand and seal at Bowie, Texas, this 10th day of February, A. D. nineteen hundred and thirty-one.

JOHN WALTER CHANCELLOR.
